UNITED STATES PATENT OFFICE.

ETIENNE RAVAZ AND AIMÉ PILLON, OF OULLINS, FRANCE.

SUPPLY-COCK FOR THE DELIVERY OF MEASURED QUANTITIES OF LIQUID.

1,401,642.

Specification of Letters Patent.

Patented Dec. 27, 1921.

Application filed June 7, 1918. Serial No. 238,715.

To all whom it may concern:

Be it known that we, ETIENNE RAVAZ and AIMÉ PILLON, French citizens, both of Oullins, Rhone, France, have invented certain new and useful Improvements in Supply-Cocks for the Delivery of Measured Quantities of Liquid, of which the following is a specification.

This invention relates to improvements in supply cocks for the delivery of measured quantities of liquid.

The supply cock which forms the object of the invention comprises simple and strong members incapable of irregular action or wedging, and is of sure working and easy control, giving at will either the maximum supply for which it has been regulated, or lesser supplies of variable volumes. In both cases it is turned off automatically as soon as the desired supply has been attained and a fresh supply, like the former or different, can only be obtained after a further adjustment of the controlling member.

The annexed drawing illustrates a water distribution cock as an example of construction of the invention. Figure 1 is a longitudinal section through the axis, the movable members having been pushed to the extreme position necessary for obtaining the maximum supply; Figs. 2 and 3 are cross sections through lines A A and B B of Fig. 1. Fig. 4 is a longitudinal section in which the movable piston is illustrated toward the end of its stroke in the working for maximum supply. Fig. 5 is a part longitudinal section showing the control of the piston by the rotation of the handle and driving rod for the minimum supplies. Fig. 6 is a front view of the handle or driving button.

The body of the cock is composed of a cylinder 1 closed at one end by a heading 1' including the tube 2 screwed on the water supply pipe 3, this cylinder has a side channel 4 of suitable section intended to convey the water into the said cylinder near the forward end of the latter and in front of the piston. The forward end of the cylinder is closed by a screw threaded stopper 5 including the delivery tube 6 and having at its center a chamber inclosing a drum 7 held in position by two packings 8, preferably of leather. This drum 7 is formed of two washers connected by a cylindrical cross-piece provided with one or more holes 9, Fig. 2; this member is so placed that this hole or

these holes are diametrically opposite to the entrance of the outlet channel 6'.

The stopper 5 is screwed on the body 1 with the interposition of a packing 10 and a metal disk 12 which has in its center a cylindrical projection 13, the edge of which is obliquely cut to form a circular double incline.

The stopper 5, the drum 7 and the disk 12 form the guide for a sliding tube 14 serving to actuate the piston 15 inserted in the cylinder 1. This tube is of determined length and it is provided, at its end which projects outside the cock, with a heart-shaped working button 16, Fig. 6. The opposite end of the said tube is screw-threaded to receive a ring comprising a projection which forms a contact member 17, the length of which is sufficient to allow its uttermost part to slide on the incline 13 when a rotatory movement is given to the tube 14. This ring secures a rubber washer 25 between it and the base of the screw-threaded part. The tube 14 is provided with a circle of holes 18 at a determined spot, so arranged that these holes come within the middle of the drum 7 when the tube 14 is completely pulled out and the contact member 17 rests on the base of the incline as shown in Fig. 4.

The piston is formed of a metal disk 15 comprising a hot pressed leather member 19 held tightly by a washer 20, the disk 15 has a central boss 21 serving as an abutment against the heading of the cylinder 1 when the piston is completely pushed back, Fig. 1; this projection also serves to center a spiral cone-shaped spring 22 inserted between the piston and the heading 1'.

In the center of the piston is screwed a rod 23 with an intermediate piece in the form of a leather or rubber rundle 24 serving as a closing-valve for the inner chamber of the sliding tube 14. The diameter of this rod 23 is much less than the inner diameter of the tube 14 in order to leave between this rod and the tube an annular space intended for the passage of the water. The rectilinear guiding of the said rod 23 is secured by a head 26 terminating the free end of this rod and of such diameter that it can slide very freely along the tube 14, while still leaving passage for the water during the course of the said rod. The rear end of this rod 23 is truncated cone-shaped for a determined length, for the purpose of gradually narrowing the an-

nular passage for the water between it and the tube 14, when the said rod reaches the bottom of its course as illustrated in Fig. 4.

A channel of small diameter 27 passes 5 completely through the piston 15 and serves as a means of communication between the compartments on both sides of the piston.

The working of the cock-system described and illustrated is as follows:

- 10 When the parts are at rest the sliding tube 14 is in the position illustrated Fig. 4 and the contact member 17 rests on the base of the double incline 13 the piston is in the position shown in dotted lines in Fig. 4.
- 15 The tension of the spring 22 holds the valve-seat 24 resting against the rear end of the tube 14 and consequently closes the entrance of the annular chamber formed by the space between the inner wall of the said tube 14 20 and the surface of the rod 23. On the other hand, the washer 25 is applied against the disk 12 and forms a joint preventing any escape of water which might be produced if the packings 8 or the tube 14 were loose.
- 25 The parts being in this position of rest, the water entering through the tube 2 and passing along the channel 4 passes through the orifice 4¹ into the free space in front of the piston between it and the disk 12, but 30 this water cannot flow out as the entrance of the tube 14 is stopped by the valve-seat 24. At this moment, if the palm of the hand is pressed on the button 16 and the tube 14 pushed inward to the bottom, the 35 piston 15 is pressed back against the heading 1¹ while fully compressing the spring 22, the spirals of which fit one within another, only forming an unimportant thickness, as is shown in Fig. 1, where the piston abuts by 40 its seat 21 against the heading 1¹. During this stroke of the piston the compartment between its front surface and the disk 12 is enlarged and is gradually filled with water which also penetrates inside the tube 45 14 by passing through the holes 18. If the handle 16 is then let go, the pressure of the water which acts on the heading of the tube 14 formed by the surface of the handle 16 forces this tube to return forward to the position shown in Fig. 4. This pressure of the water, on the other hand, compels the piston to remain flattened against the heading 1¹.

The tube 14 having taken the position in 55 Fig. 4, the water which it contains can pass through the holes 18 into the annular space 11 formed by the inside of the drum 7, then it passes through the holes 9 of the partition wall of the latter and through the annular 60 chamber 11¹ outside the said partition wall and passes out through the tube 6.

While flowing, the water which fills the body of the cock passes through the channel 27 of the piston and into the space existing 65 between the rear surface of this piston and

the heading 1¹, thus establishing a like pressure on both surfaces of the piston. The pressure of the spring 22 can therefore act on the rear surface of this piston and push the latter gradually back until the valve seat 70 24 reaches the rear end of the tube 14 and stops the entrance to the latter, thus interrupting the flow of the water.

The duration of this flow is equal to the time which the piston takes to pass over 75 the length of the cylinder 1, this time is the resultant of the force of the spring 22 on the one hand and the diameter given to the small communication channel 27 on the other hand, this channel allowing the filling 80 of the back chamber and consequently the closing stroke of the piston under the action of the spring 22. Thus with the same apparatus variable supplies can be obtained by gaging the channel 27 differently and by 85 employing springs of different strength.

The flow of water can be interrupted, if desired, it being sufficient to give the tube 14 a rotatory movement on its axis, which will cause the contact member 17 to ascend 90 on the incline 13 which will cause the tube 14 to slide from front to back and the movement of this tube being sufficient for the circle of holes 18 to leave the annular space 11 and come within the rear packing 8, it is 95 understood that the water can no longer escape. The piston will however continue its course under the action of the spring 22 until its valve seat 24 abuts against the end of the tube 14 as shown in Fig. 5. The 100 flow will be restored by bringing the tube 14 back to its former position, the piston will be again pushed by the spring 22 and automatic closing will ensue when the said piston reaches the end of its course.

The incline 13 will also allow of obtaining a very limited supply and an automatic closing when this supply has been obtained. It has been explained that the rotation of the tube 14 on its axis when it is in the position shown in Fig. 4 causes the contact member 17 to ascend the incline 13 and the tube 14 to be pushed forward. It is understood that the course of the latter will depend on the fraction of a revolution for 110 which it will be moved and that, consequently, the piston will be moved to a corresponding extent while equally compressing the spring 22. If the tube is then brought back to its original position the water will 115 flow away during the time taken by the piston to return to the position of stoppage of the sliding tube 14.

Fig. 5 shows the position of the contact member 17 at the top of the incline 13 and 120 the consequent position of the piston, which will only have a little way to go in order to stop the tube 14. This distance will be reduced in proportion as the rotation of the tube is decreased. Of course the said 125 130

tube must always be restored to its former position in order to cause the water to flow. The incline 13 being circular the top thereof will be reached by the contact 17 after 5 half a revolution of the tube 14 in one or the other direction immaterially.

After the closing of the cock has taken place automatically as has been described, a fresh flow of water is obtained by again

- 10 pushing the piston by means of the controlling button. The water which is in the compartment behind the piston would prevent the latter from moving if the hot-pressed leather member 19 did not leave a slight 15 play between its circumference and the inner surface of the cylinder, which play is sufficient for the water filling the said back compartment to pass gradually into the front compartment.
- 20 In large supply cocks, such as a water-post for instance, no play will be left between the leather member 19 and the cylinder, but the piston will be provided with packing rings in order to secure absolute 25 water-tightness, the said piston will also be provided with an opening and will include an automatic valve arranged to open at the forward movement of the piston under the pressure of admitted water and to close at 30 the return of the said piston.

The operation button 16 has been made heart-shaped in order that it may include a point intended, when it is turned downward (position in full lines), to indicate 35 that the contact member 17 is at the base of the incline, while when it is turned upward (position in dotted lines) it indicates that the contact member is at the top of this incline. In the intermediate positions 40 it also shows the corresponding positions of the contact member, as the button is so adjusted on the tube that its point coincides with that of the contact member 17. This point can serve as a pointer moving over a 45 graduated index on the front surface of the cock which will allow of always obtaining a determined volume of liquid by setting the pointer on the required mark.

The arrangement of the part 7 protects 50 the rod 23 of the piston from any tendency to wedging which might fix the piston in a position allowing a continuous outflow of water. This device, in fact, prevents any attempt to reach the said rod by means of 55 any instrument. Hence any fraud is impossible further the stopper 5 being sealed after regulating the apparatus any opening or attempt to open would be revealed by the breaking or deterioration of the seal.

60 The dimensions of the apparatus depend on the results to be obtained for example, for a like diameter of the cylinder 1 and the same dimensions of the inlet and outlet orifices for liquid, the length of the said 65 cylinder can be decreased or enlarged and

the slope of the incline can be reduced or increased, which would give a decrease or a notable increase of the supply, by combining the dimensions of the members with suitable gaging of the admission and outlet 70 of the water and the communication channel 27, together with the force of the spring 22, the supplies can be varied within wide limits.

The admission of the liquid to the body of 75 the cock can take place otherwise than through the channel 4 shown only as an example.

The device is suitable for the distribution of all liquids. It can be used, for instance, 80 for the measurement and distribution of pharmaceutic liquid products, perfumery and the like, into vials, bottles and receptacles of all shapes and capacities, which will always receive the exact amount of liquid 85 which they are to contain. The device could be automatically operated, for instance the front of the device can be provided with a screw-abutment device, sliding or otherwise, which will allow an exact and 90 variable regulation within wide limits of the course of the sliding tube 14 and consequently of the piston so as to obtain any supply between a given minimum and maximum. 95

What we claim as our invention and desire to secure by Letters Patent of the United States is:—

1. A device for delivering measured quantities of liquid comprising a body, a heading 100 fixed at one end of said body, a stopper comprising a chamber at the other end of said body, an extension on said stopper in communication with said chamber, and forming an outlet for the liquid, a tubular extension from said chamber coaxial with said body and forming a guide, a slidable and rotatable hollow rod extending through said guide into said body, said rod having a series of circumferentially arranged orifices 105 adapted to communicate with said chamber when the rod is in a certain position, a piston provided with a transverse channel within said body, a piston rod extending from said piston into said hollow rod, means 110 for guiding said piston rod in said hollow rod, a valve seat on said piston coacting with the inner end of said hollow rod, a spiral spring between the rear face of said piston and said heading, a conduit for supplying 115 liquid to said body in front of said piston, a cylindrical member having an inclined surface on said stopper and projecting into said body, and a laterally projecting member at one extremity of said hollow rod adapted to 120 slide over said inclined surface when said rod is pulled out and rotated.

2. A device for delivering measured quantities of liquid comprising a body, a heading 125 fixed at one end of said body, a stopper com-

prising a chamber at the other end of said body, an extension on said stopper in communication with said chamber, and forming an outlet for the liquid, a perforated drum 5 in said chamber, packings holding said drum in position in said chamber, a tubular extension from said chamber coaxial with said body and forming a guide, a slidable and rotatable hollow rod extending through said 10 guide into said body, said rod having a series of circumferentially arranged orifices adapted to communicate with said chamber when the rod is in a certain position, means for sliding and rotating said rod, a piston 15 provided with a transverse channel within said body, a piston rod extending from said piston into said hollow rod, means for guiding said piston rod in said hollow rod, a valve seat on said piston coacting with the inner end of said hollow rod, a spiral spring 20 between the rear face of said piston and said heading, a conduit for supplying liquid to said body in front of said piston, a cylindrical member having an inclined surface on said stopper and projecting into said body 25 and a laterally projecting member at one extremity of said hollow rod adapted to slide over said inclined surface when said rod is pulled out and rotated.

In witness whereof we have signed this 30 specification in the presence of two witnesses.
